HERMANN NEWMANN, OF NEW YORK, N. Y.

TURRET ATTACHMENT FOR ENGINE-LATHES.

1,037,298.

Specification of Letters Patent. Patented Sept. 3, 1912.

Application filed November 10, 1911. Serial No. 659,475.

To all whom it may concern:

Be it known that I, HERMANN NEWMANN, a citizen of Germany, residing at New York city, county and State of New York, have 5 invented a new and Improved Turret Attachment for Engine-Lathes, of which the following is a specification.

This invention relates to a novel turret for lathes which is adapted to be secured 10 more particularly to the slide rest of an engine lathe.

The turret comprises essentially a rotatable holder that supports a plurality of tools extending alternately in a radial and 15 axial direction.

The invention further comprises novel means for locking said holder against rotation, after a selected tool has been brought into working position.

20 In the accompanying drawing: Figure 1 is a face view of a turret attachment embodying my invention; Fig. 2 a vertical section on line 2—2, Fig. 1 showing some of the parts in view; Fig. 3 a top view of Fig. 25 1; Fig. 4 a cross section on line 4—4, Fig. 2, and Fig. 5 a rear view of Fig. 1.

My turret attachment is shown to be secured to the top slide 10 of a cross-feed slide rest 11, although it is obvious that it may 30 also be supported by a compound slide rest without departing from the spirit of my invention. Slide 10 is provided with a relatively fixed Z-shaped support 12, the upper horizontal arm of which is provided with a

35 groove 13. Into the latter is fitted the depending feather 14 of an L-shaped bracket 15, the parts 12 and 15 being held in position by a screw bolt 16 having countersunk nut 17. Bracket 15 is perforated for the 40 passage of a screw bolt 18, the head 19 of which is received within a corresponding recess of a circular tool holder 20, whereby a screw 21 tapped into said head and holder prevents an independent rotation of these 45 parts. Disk 20 is preferably slightly dished as illustrated in Fig. 2 and is provided with a plurality of spaced bosses 22 preforated as at 23, six of said bosses being shown in the drawing. Perforations 23 ex- 50 tend in parallelism with the axis of bolt 18 and are adapted for the reception of suitable tools (not shown) which may be held in position by clamp screws 24. Intermediate bosses 22, there is arranged upon holder

55 20, a plurality of radially disposed U-shaped tool clasps 25 secured to said holder by

screws 26, which are tapped into the clasps and pass loosely through elongated bores or slots 27 of the holder, to permit a slight adjustment of the tools. Owing to the slight 60 concavity of disk 20, clasps 25 assume a slight dip, so as to throw the working edges of the tools well forward of the tool holder and thus obtain a desirable clearance between the work and the holder. 65

Intermediate bracket 15 and holder 20, there is fitted upon bolt 18 a disk 28 which is connected to the holder by pins 29 so as to participate in the rotation thereof. Disk 28 is provided with peripheral notches 30, 70 the number of which corresponds to the combined number of bosses 22 and clasps 25. Notches 30 are adapted to be engaged by a detent 31 pivoted to bracket 15 at 32 and influenced by a spring 33. The threaded section of bolt 18 is engaged by a clamping nut 34 adapted to frictionally engage bracket 15 and having a neck 35 which is loosely encircled by a ring 36. The latter has a pair of lugs 37 straddling an elbow lever 38 that is fulcrumed to said lugs at 39. The upper arm of lever 38 constitutes a handle, while the lower arm is adapted to be received within either one of a plurality of transverse grooves 40 formed on the periphery of nut 34. The rearwardly protruding end of bolt 18 carries a radial pin 41 which is adapted to engage a pin 42 of nut 34 that extends in parallelism with the axis of bolt 18. 80 85 90

In use, the bosses 22 and clasps 25 hold a plurality of different tools adapted to perform the various operations in metal etc. working, the particular tool in use being always horizontally alined with bolt 18. If 95 it is desired to bring another tool carried by holder 20 into the operative position, handle of lever 38 is rotated while the lower arm of the latter is inserted into one of the grooves 40, so as to loosen nut 34, and thereby render holder 20 turnable. Lever 38 is then thrown up to release nut 34 and the latter is turned by hand to impart a corresponding rotation to holder 20 by the engagement of pins 41, 42. This rotation is continued until the desired tool has arrived at the working position, the proper horizontal alinement of said tool with the axis of the holder being ascertained by the coöperation of the notched disk 28 and de- 100 105 110 tent 31. Nut 34 is now tightened up by hand, and lever 38 is tilted until its lower

arm engages one of the grooves 40, whereby the handle of said lever is utilized for finally tightening nut 34, in which position the parts remain until a further exchange of tools is necessary when the operation described is repeated.

I claim:

1. A turret for lathes comprising a bracket adapted to be secured to a slide rest, a bolt rotatably mounted in said bracket, a tool-holder non-rotatably secured to one end of the bolt, a grooved clamping nut carried by the other end of the bolt and adapted to frictionally engage the bracket, 15 a ring encompassing the nut, and a lever pivoted to said ring and adapted to engage the nut-grooves.

2. A turret for lathes comprising a bracket adapted to be secured to a slide

rest, a screw bolt rotatably mounted in said bracket, a tool holder carried by said bolt, a grooved nut engaging the bolt, a ring turnable on said nut, and a tightening lever pivoted to said ring and adapted to engage the nut-grooves.

3. A turret for lathes comprising a bracket adapted to be secured to a slide rest, a headed screw bolt rotatably mounted in said bracket, a tool holder non-rotatably secured to the headed end of the bolt, a 30 radial pin carried by said bolt, a clamping nut engaging the bolt and having a pin that is adapted to be engaged by the first named pin, and means for tightening said nut.

HERMANN NEWMANN.
